UNITED STATES PATENT OFFICE

PERRY P. YOHE, OF NORTH HOLLYWOOD, CALIFORNIA, ASSIGNOR TO KOEHRING COMPANY, OF MILWAUKEE, WISCONSIN, A CORPORATION

CONSISTENCY CONTROLLING MECHANISM FOR CONCRETE MIXERS

Continuation of application Serial No. 268,215, filed April 7, 1928. This application filed March 1, 1930.
Serial No. 432,434.

This application is a continuation of my application Serial No. 268,215, filed April 7th, 1928, for concrete mixer, and relates more particularly to the method and apparatus 5 for determining with accuracy the consistency of concrete as it is being mixed in a concrete mixing machine.

In the art of concrete engineering, it is a well known fact that the strength of concrete primarily depends upon a certain proper ratio of water and cement during the initial mixing thereof.

Concrete when mixed with a minimum amount of water, said amount being just 15 sufficient to make the mass workable, acquires a much greater strength than concrete when mixed with a greater quantity of water, it being assumed, of course, that the quality and quantity of the other ingredients are the 20 same.

In concrete mixing apparatuses which are used today, it is practically impossible to determine with any degree of accuracy the amount of water contained in the mix. The 25 reason for this is that all of the aggregates which are used contain a certain amount of water which is commonly known as the moisture content, and this moisture content is extremely variable, not only depending upon 30 the atmospheric conditions at the time the materials are used but also upon the condition of the materials at the time they are delivered on the job. Extremely accurate measuring devices are being used today for 35 predetermining the quantity of water which goes into the mix of a particular batch of cement, but from the above, it can be readily observed that even though this quantity of water is known, when the material is introduced 40 into the mixing machine, it contains a variable quantity of water which is unknown, and, therefore, the amount of water contained in the mix is necessarily variable and unknown.

An object of my invention is to remedy the 45 above difficulties just pointed out by determining with extreme accuracy the quantity of water necessary and desirable in a mixture of cement while it is being mixed, and 50 supplying thereto that particular quantity.

Another object of my invention is to provide an apparatus for supplying to a quantity of cement as it is being mixed in the concrete mixing machine, a predetermined quantity of water, and to vary that quantity 55 of water by mechanical means directly in proportion to the quantity of water previously contained in the mixture.

A further object of my invention is to introduce into a mixing drum a quantity of 60 cement and aggregates, adding thereto sufficient water to make a thick but workable mixture, rotating the drum, predetermining from the consistency of the mix within the drum the quantity of water necessary to bring 65 the mix to the desired consistency, subsequently supplying to the mix the desired quantity, and mixing the aggregates, cement and water for a predetermined period.

A still further object of my invention is 70 to introduce into a mixing drum a certain quantity of cement and aggregates, adding thereto sufficient water to make a thick workable mass, rotating the drum to cause a mixing action, utilizing the resistance to rotation 75 of the drum which is caused by the consistency of the mixture to predetermine the quantity of water to be subsequently delivered to the drum to bring the mix to the desired consistency, permitting the mass to 80 mix a predetermined time, and adding the additional predetermined quantity of water to bring the mix to the desired consistency.

Other and further objects and advantages 85 of the invention will be hereinafter set forth and the novel features thereof defined by the appended claims.

In the drawings:

Fig. 1 is a diagrammatic elevation of a concrete paving machine, showing my invention applied thereto;

Fig. 2 is an enlarged elevation of the charging end of a concrete mixing drum, disclosing the yieldable power drive therefor, the primary water supply means therefor 95 being shown in section;

Fig. 3 is a side elevation of a mixing drum, having my improved consistency determining and water supplying apparatus applied thereto;

Fig. 4 is a top plan view of the parts as disclosed in Fig. 3;

Fig. 5 is a horizontal sectional view taken approximately on the plane indicated by the line 5—5 of Fig. 3;

Fig. 6 is a sectional view through the valve actuating control device for the supplemental water supply means;

Fig. 7 is an enlarged fragmentary detail view of a portion of the shiftable ring gear, showing the resilient driving connection for the mixing drum;

Fig. 8 is a sectional view on line 8—8 of Fig. 6;

Fig. 9 is a detail view of a conventional snap-over mechanism such as may be used for actuating the water control valves; and

Fig. 10 is a detail sectional view of the stand pipe associated with the supplemental water supply means of Fig. 1.

Like reference characters refer to like parts in the several figures of the drawings.

Referring to Fig. 1, the numeral 1 indicates an engine for furnishing the power to operate the several parts of the mixing machine in which 2 illustrates the charging skip which is shiftable to receiving and charging positions, as shown in full and dotted lines respectively.

The aggregates to be mixed are placed in this skip, together with the cement, after which the skip is elevated to the dotted line position to discharge its contents into the mixing drum 3. At the end of the mixing period, the discharge chute 5 is tilted to discharging position which directs the aggregates from the mixing drum into the distribution bucket 6. The bucket is movable along the boom to the desired place of deposit and the door in the lower portion of the bucket is opened to allow the bucket to be emptied.

The aforementioned description relates to the conventional type of paving machine to which my invention is applied.

Disclosed above the mixing drum 3, and in a position to be actuated by the skip during the charging action thereof, is a shiftable rod 4. This rod has pivoted thereto link members 4a and 4b, the free ends of which are connected to the valve members 8 and 7 respectively. To provide for instantaneous actuation of the valves 7 and 8, I may provide a conventional snap-over mechanism positioned intermediate the valves 7 and 8 and the link members 4a and 4b. A type of this snap-over mechanism is disclosed in Fig. 9 and will later be described.

The valve 7 establishes communication between the water tank 9, hereafter referred to as the primary water tank, and the mixing drum, while the valve 8 establishes communication between any suitable source of supply for furnishing water to the primary tank 9 and said tank. It will be here ob-

served that the valves 7 and 8 are set in opposition positions, that is, one valve is open when the other is closed, and vice versa. The primary water tank 9 is designed to supply a predetermined quantity of water to the mixing drum 3, as controlled by the valves 10, 11, 12 and 13. Referring to Fig. 2, it will be observed that, depending upon which of the valves just referred to is open, the water contained in the tank 9 will be discharged at the proper time through the pipes 17 into the mixing drum until the water level reaches the particular opening as controlled by the valve, whereupon further discharge will be prevented. With the valves 7 and 8 in the position shown in Fig. 2, the tank 9 will be filled from the water supply until the water level actuates the float valve 14 which is disposed in the air vent 15. The float member 16 of the float valve 14 will be then carried upwardly and cause the air vent to be closed, thus preventing the admission of additional water into the tank 9.

The rod 4 is threaded at 20a and has positioned thereon adjacent its end a clutch member 19. This clutch member is internally threaded, as indicated at 20. Freely rotatable on the rod 4 is a sprocket wheel 21 recessed at 22 to receive the clutch teeth 23 of the cylindrical clutch member 19. A compression spring 24 and washers 25 are disposed between the clutch member 19 and the extreme end of the rod 4 to maintain the clutch member 19 normally in interlocking engagement with the sprocket wheel 21. The sprocket wheel 21 is driven through the chain 28 by a friction disc 26, said disc being secured to a rotatable shaft which is, in turn, suspended from the frame of the mixer, and which has fixed thereto a sprocket 27 carrying the driving sprocket chain 28.

Disposed on the mixing drum 3 in the path of the friction disc 26 is a cooperating friction block 29 which causes intermittent rotation of the disc 26 as the drum 3 rotates. The drum 3 carries thereon a shiftable ring gear or sprocket 32. A sprocket 30 disposed on the driving shaft 30a receives the drum drive chain which, in turn, engages the ring gear sprocket 32.

The mounting of the ring gear sprocket 32 to permit relative movement thereof with respect to the mixing drum 3, is clearly seen in Figs. 3, 4, 5 and 7. The ring gear sprocket is slotted at 35 to receive the guide studs 33 which may be secured in any suitable manner, having thereon the washers 34. Disposed on the mixing drum at spaced intervals are the compression spring supports 38. Projecting from the ring gear sprocket assembly 32 are extensions 37. Compression springs 36 are positioned between the supports 38 and the extensions 37 of the ring gear to normally exert pressure tending to rotate the ring gear with respect to the mix-

ing drum to the position shown in Fig. 7 with the studs 33 engaging the ends of the slots 35. Projecting laterally from the ring gear assembly are the cam members 39.

5 Disposed on the mixing drum 3 in parallel spaced relation to the ring gear sprocket 32 is a laterally shiftable annular flanged ring 43. The flanged ring carries a plurality of actuating rods 41 which project toward the 10 cams 39 carried by the ring gear sprocket 32. The rods 41 are slidably positioned in brackets 42 carried by the mixing drum 3 and are urged toward the ring gear sprocket 32 by the springs 45 which engage the brackets 15 42 and the collars 41a carried by the rods 41. Rollers 40 are pivotally secured to the ends of the rods 41 to provide an anti-frictional contact between the aforementioned rods and the cam members 39.

20 The radial flange of the ring 43 lies to the right and adjacent the arm 44 fixed to a rod 46 slidably carried in brackets 47 on the frame of the mixing machine. This rod 46 is clearly seen in Fig. 3 of the drawings and 25 constitutes part of the setting mechanism for the secondary water supply device which will hereinafter be described. A spring 68 is disposed between one end of the rod 46 and one of the brackets 47, maintaining the rod 30 with its arm 44 resting against the flange of the ring 43. Pivoted to a collar which is fixed to the rod 46 is a link 48 which is, in turn, pivoted to the gear segment 49. A pinion 52 meshes at one side with the gear 35 segment 49 at the other side with a vertically disposed rack 53 which is carried by a rod 54 disposed for vertical movement in the brackets 55. The rod 54 constitutes a movable support for the four-way casting 56. The four- 40 way casting 56 is hollow, having projecting upwardly therefrom the vertical stand pipe 56a containing a float valve 56b, and is provided with flexible conduits 57 and 58. These conduits are connected to the secondary water tank 61 which is rigidly carried by the 45 framework of the mixing machine in any suitable manner, such as by the brackets 62. A float operated vent valve 65 is disposed in the tank 61 to be closed when the water level 50 reaches the top of the tank. Discharge and intake conduits 59 and 60 also communicate with the four-way casting 56 and include flexible portions 59a and 60a. Disposed in the conduit 59 is the control valve 67, while 55 a similar control valve 66 is disposed in the inlet conduit 60.

These last named valves 66 and 67 are disposed in opposite relation, that is, when one valve is open the other is closed, and vice 60 versa. These valves may be also provided with snap-over mechanism similar to that described with respect to the valves 8 and 7, so that they will remain in either their open or closed position.

65 The rod 4 also constitutes the actuating

mechanism for the valves 66 and 67, as well as the valves 7 and 8. The levers 63 connect the valves 66 and 67 with the rod 4 so that as the rod is moved in one direction the snap-over mechanisms for the valves 66 and 67 70 operate to shift the valves in one of their alternate positions, while when the rod 4 is moved in the other direction, the valves will be shifted to the other alternate position.

It should be here observed that the vertical disposition of the casting 56, as determined by the adjustment of the rack 53, will govern or predetermine the quantity of water delivered from the supplemental tank 61, since after the tank is filled and the valve 67 is opened by movement of the rod 4 to the right, as shown in Figs. 3 and 4, water will flow out of the tank 61 until the level reaches that of the casting 56, at which time air entering through the stand pipe 56a will break the seal and discontinue the siphoning action of the pipe 59 leading into the pipe 17 which enters the mixing drum 3. As shown in Fig. 3, the parts are at rest with the casting 56 disposed above the tank 61, but it should be here noted that when the cement is being mixed in the drum 3, the resistance of this mass to rotation of the drum will cause a relative shifting of the ring gear 32 and cams 39 carried thereby which will actuate the rods 41 to move the annular flanged ring 43 to the left. As the flange is moved to the left, the rod 46, through its link connection 48, will shift the gear segment 49 in an anti-clockwise direction, causing the casting to be lowered to some predetermined point below the top of the tank 61. This point is, of course, dependent upon the relative movement of the ring gear 32 with respect to the drum 3 incident to the resistance to rotation as offered by the consistency of the mass contained in the drum 3.

Referring again to Figs. 3, 4, 5 and 6, it should be noted that the cylindrical clutch member 19 constitutes a sort of timing mechanism for the valves 7, 8, 66 and 67. This mechanism will now be described in detail:

As the drum 3 rotates, the friction block 29 engages the friction disc 26 to rotate the same an increment of movement for each revolution of the mixing drum 3. The rotation of the friction disc 26 actuates the sprocket 27 and through the chain 28 rotates the sprocket wheel 32. When the cylindrical clutch member 19 is in the position shown in Fig. 6, this member is also rotated as the drum rotates, since the spring 24 causes the clutch teeth 22 to engage the recesses 23 in the rotating sprocket wheel 21, the threaded portion 20 of the cylindrical clutch member 19 maintaining the rod 4 in unthreaded relation thereto, as shown. It should be here observed that when the rod 4 is moved inwardly or to the left from the position shown in Figs. 3 and 5, the threaded portion on the 115 120 125 130

rod 4 will engage and force the cylindrical clutch member 19 away from the sprocket wheel 21, whereupon the spring 24 will become effective to cause the clutch member 19 to be rotated by the screw threads 20a carried by the rod 4 as the clutch member screws itself on the said threads. This action takes place as the skip 2 is raised to charge the mixing drum 3. Simultaneously with the movement to the left of the rod 4, as above described, the valves 7, 8, 66 and 67 are actuated. The valve 7 is shifted from closed position to open position to permit the primary water tank 9 to discharge its contents into the mixing drum, while the valve 8 is simultaneously shifted to close the communication between the primary tank and the supply line 8a. The valve 66 is also simultaneously opened to permit water to flow from the intake supply pipe 60 into the secondary water tank 61, while the valve 67 is closed to prevent the escape of water from the secondary tank into the pipe 17. It will be here observed that as the primary tank 9 is discharging, the secondary tank 61 is filling.

Due to the intermittent rotation of the sprocket wheel 21, the cylindrical clutch member 19 will be rotated thereby when the skip 2 is lowered to permit the spring 4c to move the rod 4 to a position where the clutch teeth 22, carried by the cylindrical clutch member, engage the recesses 23 in the sprocket wheel 21. As the cylindrical clutch member 19 rotates, the threads 20a on the rod 4 will gradually be unscrewed from the threads 20 on the cylindrical clutch member 19, which produces a gradual movement to the right of the rod 4. During the movement of the rod 4 to the initial position, as shown in Figs. 3, 4 and 5, the valves 7, 8, 66 and 67 will again be actuated to establish communication between the supply line 8a and the primary water tank 9 and establish communication between the secondary water tank 61 and the discharge conduit 59 which leads into the pipe 17 and from there into the mixing drum. The other two valves 7 and 66 are closed, which prevents any additional water from being discharged from the primary tank 9 as this tank is being filled, and also prevents any additional water from being supplied to the secondary tank 61 as this tank is being discharged. It should be further observed that a predetermined period of time will elapse between the movement of the rod from the left hand position thereof due to the impingement of the skip thereagainst, to the final restoring of the rod incident to the rotation of the cylindrical clutch member 19, and this period represents the interval of time between the discharge of the water from the primary water tank until the discharge of the water from the secondary water tank. The reason for this is as follows:

As the skip is elevated to charge the drum with aggregates and cement to be mixed, the rod when moved inwardly, or to the left, discharges the contents of the primary water tank to provide an initial mixing of the aggregates and water to form a preliminary mixture, so to speak, to determine the amount of water necessary for the final mixture. The resistance to rotation of the drum by this preliminary mixture causes the secondary water measuring device to be adjusted, and as the rod 4 is slowly screwed to the left by the threads 20 of the cylindrical clutch member 19, the valves 7, 8, 66 and 67 will, after a certain period of time, be shifted to permit this secondary quantity of water to be discharged into the mixing drum.

Describing briefly the conventional snap-over mechanism shown in Fig. 9, each of the valves for controlling the intake and discharge conduits of the primary and secondary water tanks carries fixed to the stem thereof a lever 75 which operates between the stop members 76 carried by a plate 77 fixed to the framework of the mixer support. Each of the rods for operating the valves is connected to a lever 78 freely pivoted to the stem of the valve. A spring 79 is connected between the end of the lever 78 and the end of the lever 75 fastened to the valve stem. As the lever 78 is shifted to dotted line position shown in this figure, the spring will pass beyond the pivotal center of the levers 75 and 78 to cause the lever 75 for actuating the valve to swing rapidly to the dotted line position shown in this figure.

Describing the complete cycle of operation of my invention, it should first be understood that the primary tank 9 is filled with water and the valves 10 to 13 properly adjusted to deliver just the sufficient quantity of water into the mixing drum to provide a thick but workable mix, the skip having been loaded with the desired mixture of aggregates and cement. The operator now throws in the skip hoist clutch, not shown, to elevate the skip to the charging position shown in dotted lines in Fig. 1 of the drawings. As the skip reaches this position, it impinges the rod 4, forcing the same to the left.

Referring now to Figs. 3 to 5, it will be observed that as the rod 4 moves to the left, the valves 7 and 8 will be actuated to interrupt the communication between the supply and the primary tank 9 and establish communication between said tank and the mixing drum to discharge a predetermined quantity from the tank into said drum. As the rod 4 is moved to the left, the spring 4c is compressed and the clutch member 19 disengaged from the sprocket wheel 21. This causes the spring 24 to screw the clutch member 19 on the threads 20 of the rod 4.

The valve members 66 and 67 are also ac-

tuated to cause the filling or charging of the secondary water tank 61.

As the skip 2 is lowered from its impingement against the rod 4, the spring 4c will move the rod to the right causing engagement between the clutch member 19 and the sprocket wheel 21, which is, as previously pointed out, intermittently rotated by the mixing drum 3. This intermittent rotation of the clutch member 19 causes the rod 4 to be gradually moved back to its initial position, as shown in Fig. 4 of the drawings, but previous to the complete restoration of the rod 4, the mixture of aggregates and water within the drum 3 causes a certain amount of resistance to rotation of the drum to be effected.

Since the drum is being rotated by the ring gear 32, which is yieldably disposed for relative movement on the drum, this ring gear will be shifted to a degree in direct ratio to the relative consistency of the mixture within the drum.

The shifting of the ring gear 32 adjusts the cams 39 which, in turn, move the annular flanged ring 43 to the left, causing the rod 46 to actuate the segment 49. Movement of the segment 49 rotates the pinion 52, lowering the rack 53, which causes the casting 56 to be positioned below the level of the water in the now filled supplemental tank 61. The rod 4, as it is being slowly moved to the right, now actuates the valves 66, 67, 7 and 8 to restore them to their original positions, namely, to establish communication between the supplemental tank 61 and the mixing drum 3 and cut off the water supply to this tank, while the valves 7 and 8 close the communication between the primary tank 9 and drum and establish communication between the supply 8a and the tank.

Water will now flow out of the tank 61 into the casting 56 and down into the mixing drum 17 until the water level drops below the position of the casting 56, as determined by the consistency of the preliminary mixture within the drum 3. When the water level within the tank 61 drops below that of the level of the casting 56, air will be admitted through the stand pipe 56a to break the siphon in the pipe 59, preventing any further discharge of water from the secondary tank.

Since these conduits are comparatively large in diameter, the flow of water will be comparatively rapid and the predetermined quantity will be discharged into the mixing drum before it can become mixed to any extent with the preliminary cement mixture, and, therefore, cannot effect a subsequent adjustment of the casting 56 until after the predetermined quantity of water has been discharged from the secondary water tank 61. After the secondary quantity of water has been added to the mixture, the mixing of the aggregates in the drum may be continued through a desired period of time, after

which the drum is discharged and it is then ready for another charge of aggregates, whereupon the cycle is repeated.

While the specific details of construction have been herein shown and described, the invention is not confined thereto as changes and alterations may be made without departing from the spirit thereof as defined by the appended claims.

Having thus described my invention, what I claim as new and desire to secure by Letters Patent is:

1. The method of predetermining the consistency of a mixture of cement, aggregates and water which consists of placing the said elements in a moving vessel, utilizing the resistance to movement of the vessel offered by the mixture therein to predetermine the quantity of water to bring the mixture to a known consistency, and supplying said quantity of water to the mixture as determined by the said resistance.

2. In a concrete mixing apparatus, the combination of a mixer, secondary water supply means for supplying a variable quantity of water to the mixer, and consistency determining means including a part connected with said mixer and movable according to the resistance to the movement of the mixer, and a connection between such part and said water supply means to actuate the latter and thus control the quantity of water to be delivered therefrom by said consistency determining means.

3. In a concrete mixing machine, a mixing drum, means for rotatably supporting said drum, water supply means, means for driving said drum, and a resilient driving connection between said drum and said driving means, together with operating connections from the driving connection to the water supply to control admission of water to the drum and thus control the consistency of a mixture of cement, aggregates and water when mixed within the drum incident to relative movement between the resilient driving connection and the drum.

4. In a concrete mixing machine, a support, a mixing drum rotatably carried thereby, water supply means for supplying water to said drum to produce a preliminary mixture when cement and aggregates are placed within the drum, means for determining the consistency of the preliminary mix, means operable by the consistency determining means to measure a predetermined quantity of water to be later supplied to the mixture to reduce the consistency of the mixture to a predetermined degree, and control means for discharging said predetermined quantity of water into the preliminary mixture, said control means being operable after a predetermined lapse of time.

5. In a concrete mixing machine, a mixing vessel, a charging device therefor, a primary

70

water supply means for supplying a measured quantity of water into said mixing vessel to produce a preliminary mixture when aggregates and cement are contained therein, 5 a secondary water supply means to supply a variable quantity of water to said vessel, means for determining the consistency of the preliminary mixture within the vessel, said means being adapted to adjust the secondary 10 water supply means, means operable by the charging device to discharge the primary water supply means, and a time controlled discharge means for discharging said secondary water supply means adapted to be set into 15 operation by said charging device.

6. In a concrete mixing machine, a mixing drum, a charging skip for introducing dry aggregates of a concrete mixture into the drum, a water tank for introducing a predetermined quantity of water into the drum to form a preliminary mixture, means operable by the charging skip to cause discharge of said tank, means to measure a variable additional quantity of water to be later supplied to said mixture to bring said mixture to a predetermined consistency, and time controlled means for discharging said variable additional quantity of water after a predetermined time, said means being initiated into 30 operation incident to movement of the charging skip.

7. In concrete mixing machines, a mixing drum, power means for rotating the drum, a yieldable drive connection between said power means and said drum, means opposing said yielding action, and means for supplying a predetermined quantity of water to said drum variable in accordance with the degree of movement between the drum and said yieldable drive means.

8. In a concrete mixing machine, a rotatable mixing drum, a charging skip for introducing aggregates and cement into the drum to be mixed thereby, water supply means for supplying mixing water to the aggregates within the drum, power means for actuating said mixing drum and said charging skip, a timing device for causing said water supply means to discharge into said mixing drum after a predetermined lapse of time, and means for setting said timing device into operation incident to charging action of the charging skip.

9. In a mixing machine, a mixing drum, water and aggregate supply means for charging said drum with an admixture having an unknown water content, shiftable consistency determining means for determining the water content of said admixture when mixed by the drum, and supplemental water measuring means associated with and controlled by the consistency determining means and operable to supply a predetermined quantity of water to the admixture within the drum to bring the moisture up to a known content.

10. In a concrete mixing machine, a mixing device, driving means for actuating the mixing device, a yieldable drive connection between the driving means and the mixing device, resilient means to resist movement therebetween, a water measuring device for supplying variable quantities of water to the mixing device, and a connection between the water measuring device and the yieldable drive connection to cause the water measuring device to be set to deliver a certain predetermined quantity of water to the mixing device incident to a certain degree of movement of the yieldable drive connection. 75

11. In a concrete mixing device, a charging skip for introducing aggregates to be mixed into the device, a water measuring tank for supplying a predetermined quantity of water to the mixing device, said quantity being less than the amount necessary to bring the mixture in the mixing device to the desired consistency, valve means associated with the tank for discharging the contents thereof into the mixing device and operable by the skip, a resilient yieldable driving means for operating the mixing device, a supplemental water tank for supplying an additional quantity of water to the mixing device, valve means associated with the supplemental tank, power means for operating the said secondary tank valve to discharge the same, and a timing device associated with said power means to render the same operative, said timing device being initiated into operation incident to charging action of the charging skip. 80 85 90 95 100

12. In a concrete mixing machine, a mixing device and support therefor, primary and secondary water supply means for supplying water to said mixing drum, a control member associated with said water supply means movable in one direction to discharge water from one of said water supply means and movable in another direction to discharge water from another of said water supply means, a measuring device associated with one of said water supply means, a yieldable power driving connection for the mixing device, and an operating connection between said yieldable power driving connection and said measuring device. 105 110 115

13. In a concrete mixing machine, a mixing device and support therefor, a charging device carried by the support for introducing aggregates and cement to be mixed with in the mixing device, primary and secondary water supply means for supplying water to the mixing device, a measuring device associated with said secondary water supply means for varying the quantity of water delivered therefrom, means carried by the mixer support for alternately operating said water supply means to discharge the same, said last named means being operable in one direction incident to charging action of the charging device to discharge the primary 120 125 130

water supply means and operable in another direction incident to mixing action of the mixing device to discharge the secondary water supply means, yieldable drive means for the mixing device, and a connection between the yieldable drive means and the secondary water measuring device for varying the quantity of water to be delivered therefrom incident to relative movement of the 10 yieldable drive means and the mixing device.

14. The method of mixing concrete which comprises introducing into a mixing drum a quantity of cement and aggregates, adding thereto sufficient water to make a thick but workable mixture, rotating the drum, predetermining from the resistance to rotation of the drum arising from the consistency of the mix within the drum the quantity of 15 water necessary to bring the mix to the desired final consistency, supplying to the mix this determined quantity of water, and mixing the aggregates, cement and water for a predetermined period of time.

20 15. The method of mixing concrete which comprises introducing into a mixing drum a quantity of cement and aggregates, adding thereto sufficient water to make a thick but workable mixture, rotating the drum to produce a mixing action, predetermining from 25 the resistance to rotation of the drum set up by the consistency of the mass the quantity of water to be added to the mixture to bring it to the proper final consistency adding the 30 predetermined quantity of water, and mixing the mass for a period of time, after adding the said additional predetermined quantity of water to bring the mix to the desired 35 consistency.

40 In testimony whereof I affix my signature.
